Application December 20, 1949, Serial No. 134,055

4 Claims. (Cl. 98—116)

1

This invention relates to an automatically opening and closing shutter for a ventilating or exhaust fan. A primary purpose of the invention is to provide a shutter construction which, automatically opening under pressure of air delivered from the fan, will open to give an absolutely clear area over the full cross-sectional air flow, at least equal to the diameter of the fan itself.

Heretofore, transverse louvers have been employed in such manner that while they open automatically upon air flow, the louvers are extended across the air flow and therefore offer considerable resistance to that flow and actually cut down the effectiveness of the fan. Moreover such louvers have developed fluttering with consequent noise and rattle particularly after a short period of usage.

A further primary object of the invention is to provide a structure which will be absolutely quiet in operation. The invention provides a means of eliminating the conventional type of plenum chamber, and it permits a great lowering of the cost of installation.

One of the primary features of the invention resides in the fact that there are but two doors or shutters employed, and each of these shutters are hinged at opposite sides to approach a common meeting line across the delivery side of the fan, and the mounting is such that when these two shutters approach their full opened positions, they are substantially balanced upon their hinge axes. These shutters are opened automatically by pressure of air generated by the fan, and they are closed beginning initially with spring urging, and completing the closing operation under the influence of gravity.

One particular form of the invention is herein illustrated and described as being applied to a mounting wherein the air flow is in a general vertical direction. This particular flow is that which would be had when the entire structure to be described is mounted over a hatchway such as would be presented in exhausting air from a room, through the ceiling, and into the attic.

Referring to the drawings,

Fig. 1 is a top plan view in partial section of a structure embodying the invention;

Fig. 2 is an end elevational view in partial section;

Fig. 3 is a side elevational view;

Fig. 4, a detail on an enlarged scale in section on the line 4—4 in Fig. 1; and

Fig. 5, a detail also on an enlarged scale in section on the line 5—5 in Fig. 2.

2

The same general fan housing and mounting structure as herein shown is shown and described in our application filed December 20, 1949, Serial No. 134,054, for Ventilating Fan Mounting Structure, now Patent Number 2,573,145. In the essential details for the purpose of explaining the present invention, there is a rectangular box generally designated by the numeral 10 which is open from the underside to have the lower edge portion 11 surround a hatchway.

There is a Venturi member 16 extending across the inside of the structure 10 to be mounted in any suitable sound insulating manner on the box 10, such as is described and shown in the copending application. A fan generally designated by the numeral 13 is mounted to revolve on a vertically disposed shaft 14, and the fan 13 is mounted to extend partially at least into the opening 15 of the Venturi member 16, the upper discharge end of this member 16 being adjacent the top edge portion of the box member 10.

Across the top side of the box 10, otherwise normally open, are a pair of shutters 17 and 18. These shutters 17 and 18 when placed over the top side of the box 10 have their opposing edges 19 and 20 brought substantially into contact one with the other across a centrally disposed line 21 which would intersect the extended axis of the shaft 14. The marginal portions of these shutters 17 and 18 will extend over the top edge portion 22 of the box 10, Fig. 1, a distance, and the outer edge portions of these two shutters 17 and 18 are provided respectively with downwardly turned flanges 23 and 24, each extending from the line 21 on the three remaining edge portions of those shutters. As indicated primarily in Fig. 1, these flanges 23 and 24 are in spaced relation from the marginal edge portion or flange 22 of the box 10. The flange 22 constitutes in the present showing, an outwardly turned flange extending horizontally from the box 10 entirely therearound.

Both of these shutters 17 and 18 are hinged to the box member 10 in an identical manner. In describing the hinging connection, reference is made to the shutter 18, to which at its outer side corners, are respectively secured the hinge brackets 25 and 26. These brackets 25 and 26 are identical with the exception that they are made in right-and-left-hand forms. Referring to Fig. 4, the bracket 25 consists of a side leg 27 turned at right angles from a hinge leg 28. The upper ends of these members 27 and 28 fit within the downturned flange 24 of the shutter 18 and

are secured thereto in any suitable manner such as by welding. With the shutter 18 in its normal, closed position when the fan 13 is inoperative, the leg 27 will extend in vertical parallel and spaced relation from the side of the box 10, and the hinge leg 28 will likewise extend downwardly in spaced parallel relation from the end of the box 10.

A bracket 29 such as a casting is secured in each instance on the opposite ends of the box 10 to have a pair of spaced apart fingers 30 and 31 extending therefrom in spaced and parallel relation from and to the ends of the box 10, Fig. 5. These brackets 29 each have mounted between their fingers 30 and 31 a bearing sleeve 32 which has an enlarged central cylindrical portion 34 against the ends of which the fingers 30 and 31 bear to have the reduced portions extending from that central portion 34 extend through the fingers 30 and 31. A bolt 33 extends axially through the bearing member 32 to compressibly urge the fingers 30 and 31 against that central portion 34, as a means of limiting the spacing to be had between those fingers.

The hinge leg 28 has its lower portion revolvably fitted with a running fit over this cylindrical portion 34 and retained thereon by extending between the fingers 30 and 31. Thus the brackets supporting the shutter 18 are restrained to rock on the horizontal axes of the bolts 33 in each instance. The shutter 17 is mounted in the same manner.

It is to be noted that the axes of the bolts 33 are spaced a considerable distance downwardly below the top edge portion 22 of the box 10 and also spaced inwardly from the sides thereof. The axes of the bolts 33 are purposely located so that the shutters may be rocked to critical open positions as indicated by dash lines, Fig. 2, in which positions for each shutter, a plane including the center of mass of the shutter and the axis through its supporting bolts 33 is substantially vertically disposed. In these positions, the shutters are practically balanced and have no tendency to rock either to a more fully open position or toward a closed position.

As indicated in Figs. 3 and 4, the lower edge portions of the bracket legs 27 terminate in a horizontally disposed and outwardly turned lip 36. This lip 36 is spaced above the common line of the axis of the bolts 33 a distance which will cause the lips 36 to strike against the box 10 when the shutters 17 and 18 are rocked a sufficient distance from their closed to fully opened positions. These lips 36 prevent the shutters 17 and 18 from reaching those open positions whereby they would tend to be such that the shutters would become completely overbalanced and tend to swing outwardly around and downwardly from the sides of the box 10. That is, the lips 36 limit the openings of these shutters 17 and 18 to those positions, from which they would normally drop by gravity if released toward the closed positions.

Each shutter 17 and 18 has secured to its outer downturned flange portions 23 and 24 one or more springs, herein shown as two each carrying the designated numeral 37.

A peculiar mounting of these springs 37 is had in that each one is positioned by being interconnected by one end to the box top edge portion 22 at a position longitudinally spaced from its other end which is connected to the flange 23 or 24 as the case may be. This mounting results in holding the springs 37 clear from overlapping on the box edge portion 22 when the shutters 17

and 18 approach and reach their closed positions. The springs 37, with the shutters 17 and 18 closed, lie parallel to and between the flanges 23 and 24 and under the edge portion 22. In these closed shutter positions, the springs 37 are under just enough tension to keep them from bowing from their axial straight line conditions and rattling, and in any event immediately resisting under slight tension, the opening of the shutters.

This initial tensioning of the springs 37 may be variably had and fixed by providing an L-shaped tab 41 having a top leg 42 resting on the top side of the box edge portion 22, from which leg 42 a second leg 43 turns downwardly through a slot 44 in the portion 22; fixing the leg 42 to the portion 22 at the desired position such as by welding; and hooking the spring 37 to the downturned leg 43; Figs. 1 and 4. The variation in spring tension is secured by selective engagement of the spring 37 in any one of the shutter flange holes 37a.

Preferably these springs 37 are spaced apart to be adjacent the downturned bracket legs 27, Fig. 3. Furthermore, the shutters 17 and 18 would normally tend to remain in their fully open positions when the lips 36 strike and rest against the sides of the box 10. This is prevented however by reason of the light and yielding pull of these springs 37 which are then in diagonally, extended positions.

When the shutters 17 and 18 are rocked from those upper and fully opened positions, and the centers of mass of the shutters 17 and 18 are carried past the vertical planes through the bolts 33, the springs 37 continue to exert a slight increasing pull on the shutters resisting further opening of the shutters 17 and 18 as they might otherwise tend to tip past those planes out of the path of the current of the delivered air. By reason of the mounting of the springs 37 to provide diagonal pulls on the shutter flanges 23 and 24 in their open positions, the pull of the springs does not increase at the same rate as it otherwise would if the springs operated with their pull entirely normal to the axes of rotation. By this "diagonal" pull means, the spring action is held down to a minimum in the initial shutter opening and is increased rapidly at the shutter positions tending to be removed from the pressure of the delivered air current.

Starting with the shutters 17 and 18 in their closed positions, Fig. 1, and the fan 13 inoperative, the entire area across the opening of the box 10 and primarily across the opening 15 of the Venturi-plate 16 will be closed off by the shutters 17 and 18 against the flow of any air therethrough, particularly from the top side downwardly, and likewise dust, foreign matter, and insects will be prevented from travelling downwardly through the box 10 from the upper side thereof by reason of the closure of those shutters 17 and 18.

When the fan 13 is set into operation to discharge a column of air upwardly from the Venturi member 16 through the opening 15, pressure is then generated immediately against the undersides of the shutters 17 and 18. As the pressure is built up, the shutters 17 and 18 will start to rock about their hinged axes defined by the lines through the bolts 33 in each instance. The shutters 17 and 18 will rock to their open positions, bringing the stop lips 36 close to their limiting degrees of travel against the sides of the box 10, with that travel being gradually braked by rea-

son of the increasing resistance of the springs 37 coming into play toward that end of travel. Normally the lips 36 will not completely strike the sides of the box 10 by reason of the resistance of these springs 37. However initially under the inertia effect of shutter travel, they will swing quite close to the box, and then be rocked outwardly therefrom to some such positions as indicated in Fig. 4, so that there will be no bumping action of these lip portions 36 against the box when the device is in operation. The shutters 17 and 18 being divided across the central line 21 will be swung to their open positions as indicated by the dash lines in Fig. 2, so that the edges 19 and 20 will be completely at the outside edge of the column of air being forced upwardly from the fan 13 from the Venturi member 16, thereby being completely removed from the central area of that column of air, and thus offering no resistance directly thereacross.

When the fan 13 is to be de-energized, the fan 13 will under the stored up inertia effect slow down gradually, and as it slows down, the air pressure directed toward the shutters 17 and 18 will likewise diminish, and under the influence of gravity aided by the springs 37, the shutters 17 and 18 will swing downwardly in accordance with that diminishing pressure, and come to rest in their closed positions over the box 10. As indicated in Fig. 2, bumpers 40 made out of any suitable resilient material such as felt or rubber may be positioned to intervene between the shutters 17 and 18 adjacent the dividing line 21 so as to cushion the fall of the shutters 17 and 18 as they reach the positions where the air pressure will no longer support them, and they will drop accordingly. The bumpers 40 are provided simply to remove the noise that might be occasioned in that slight degree of travel at the end of the operation.

Thus it is to be seen that we have provided a structure wherein there are a minimum number of shutters, two at most, operating automatically with the flow of air exhausted from a fan, and also operating so as to be completely removed from any positions transversely across the flow of that air. Furthermore, it is to be seen that the shutters when in their opened positions actually float against the pressure of the air flow without being permitted to bang against metallic parts, and are further aided in closing by reason of the springs initially starting that closing action, but the springs being substantially reduced in operation and the closing operation confined substantially to the action of gravity in the final travel of the shutters.

While we have shown our invention in the one best form as now known to us, it is obvious that structural variations may be employed without departing from the spirit of the invention, and we therefore do not desire to be limited to that precise form beyond the limitations which may be imposed by the following claims.

We claim:

1. Means for automatically opening and closing a fan discharge opening depending upon fan operation, comprising a mounting box bounded by side walls to define top openings at opposite ends one of said openings being a top opening; a fan mounted within the box to discharge toward said top opening; a pair of shutters dimensioned to lie normally closed across said top opening and meet substantially by free inner edges on a center line thereacross; hinge legs extending from opposite corners of said shutters

removed from said meeting line and down along those side walls of the box over which said center line runs; hinge means carried by said side walls interengaging end portions of said legs whereby said shutters may be rocked thereon on a common axis in each instance from said closed positions to open positions whereby a plane through the center of mass of a shutter and said axis may be vertically disposed; stop means carried by said shutters to abut walls of the box in the path of travel of the shutters to open positions, said stop means being located to stop the opening travel of the shutters at approximately those positions where their said free edges are tangential to the perimeter portion of the flow stream from said opening; and spring means interconnecting between said shutters and said box, yieldingly resisting opening travel toward said stop means limiting positions, and holding 10 said free edges against said flow portion to maintain said stop means in normally spaced relation from said walls; said spring means in each instance consisting of at least one tension spring interconnecting by one end with the discharge 15 end of said box at one point and by its other end at a point along the outer edge portion of a shutter, said two points being spaced apart longitudinally of the shutter whereby the spring lies parallel thereto when the shutter is closed.

2. Means for automatically opening and closing a fan discharge opening in response with air flow therethrough, comprising a fan; a fan discharge box having a top opening bounded by a box edge; a pair of shutters normally lying 20 in substantially horizontal planes and covering said opening, said shutters substantially meeting by inner opposing edges along a center line across the opening; means hingedly mounting said shutters to swing upwardly by their opposing edges 25 from said center line, comprising for each shutter, legs fixed to and downwardly turned from the shutter to extend below said box opening edge; hinge pins engaging said legs to define a hinge axis spaced inwardly under and below the outer edge portion of the shutter, said axis being 30 parallel to said center line and being located intermediate the center of mass of the shutter and said outer edge portion when the shutter is in its closed position; said hinge axis being located to permit said shutter in each instance to be shifted under full air discharge conditions to have a plane through said axis and said center of mass vertically disposed with the shutter in a position inclined from the vertical over said 35 box.

3. Means for automatically opening and closing a fan discharge opening in response with air flow therethrough, comprising a fan; a fan discharge box having a top opening bounded by a box edge; a pair of shutters normally lying 40 in substantially horizontal planes and covering said opening, said shutters substantially meeting by inner opposing edges along a center line across the opening; means hingedly mounting said shutters to swing upwardly by their opposing edges from said center line, comprising for each shutter, legs fixed to and downwardly turned from the shutter to extend below said box opening edge; hinge pins engaging said legs to define 45 a hinge axis spaced inwardly under and below the outer edge portion of the shutter, said axis being parallel to said center line and being located intermediate the center of mass of the shutter and said outer edge portion when the shutter is in its closed position; said hinge axis

being located to permit said shutter in each instance to be shifted under full air discharge conditions to have a plane through said axis and said center of mass vertically disposed with the shutter in a position inclined from the vertical over said box; stop means limiting opening travel of the shutters to positions between vertical shutter positions and said full air discharge, inclined positions; and spring means resisting travel of the shutters from said inclined positions toward said vertical positions.

4. Means for automatically opening and closing a fan discharge opening in response with air flow therethrough, comprising a fan; a fan discharge box having a top opening bounded by a box edge; a pair of shutters normally lying in substantially horizontally planes and covering said opening, said shutters substantially meeting by inner opposing edges along a center line across the opening; means hingedly mounting said shutters to swing upwardly by their opposing edges from said center line, comprising for each shutter, legs fixed to and downwardly turned from the shutter to extend below said box opening edge; hinge pins engaging said legs to define a hinge axis spaced inwardly under and below the outer edge portion of the shutter, said axis being parallel to said center line and being located intermediate the center of mass of the shutter and said outer edge portion when the shutter is in its closed position; said hinge axis being located to permit said shutter in each instance to be shifted under full air discharge

conditions to have a plane through said axis and said center of mass vertically disposed with the shutter in a position inclined from the vertical over said box; stop means limiting opening travel of the shutters to positions between vertical shutter positions and said full air discharge, inclined positions; and spring means resisting travel of the shutters from said inclined positions toward said vertical positions; said 10 spring means comprising a tension spring for each shutter, one end of the spring being carried by said box, and the other end by said shutter outer edge portion, the axes of the springs being diagonally disposed in reference to said center line by having the spring ends spaced apart longitudinally of the shutters.
